UNITED STATES PATENT OFFICE.

JOHN BERGESEN, OF BROOKLYN, NEW YORK.

UMBRELLA.

SPECIFICATION forming part of Letters Patent No. 433,270, dated July 29, 1890.

Application filed January 11, 1890. Serial No. 336,646. (No model.)

To all whom it may concern:

Be it known that I, JOHN BERGESEN, of Brooklyn, in the county of Kings and State of New York, have invented a new and Improved Umbrella, of which the following is a full, clear, and exact description.

The object of the invention is to provide a new and improved umbrella which is simple and durable in construction and can be readily folded up when not in use for conveniently carrying it in a pocket, valise, or other suitable receptacle.

The invention consists of certain parts and details and combinations of the same, as will be hereinafter fully described, and then pointed out in the claims.

Reference is to be had to the accompanying drawings, forming a part of this specification, in which similar letters of reference indicate corresponding parts in all the figures.

Figure 1 is a sectional side elevation of the improvement as folded up. Fig. 2 is a similar view of the same as extended. Fig. 3 is an enlarged face view of the crown-piece. Fig. 4 is a like view of the brace-piece. Fig. 5 is an enlarged sectional side elevation of the outermost cane-section. Fig. 6 is a transverse section of the same on the line $x-x$ of Fig. 5. Fig. 7 is a sectional plan view of the same on the line $y-y$ of Fig. 5. Fig. 8 is an enlarged sectional side elevation of part of the outer and middle sections when extended, and Fig. 9 is a sectional plan view of the same on the line $z-z$ of Fig. 8.

The improved umbrella A is provided with a cane or stick made in three sections adapted to telescope one in the other, and of which the lowermost or handle section B is provided on its outer end with a suitable handle, and is held to slide in the middle section C, in the upper end of which is held to slide the outermost section D, adapted to pass into the upper end of the handle-section B, as is plainly shown in Fig. 1. On the upper end of the outermost section D is secured the crown-piece E, to which are pivoted the ribs F, each made in two parts F' and F'', of which the upper end part F' is pivoted in the crown-piece E, while its lower end is pivoted to a joint-plate G, on which is also pivoted the upper end of the outer part F''. Each joint-plate G

is pivotally connected with a brace H, pivoted at its inner end to the brace-piece I, secured in the upper end of the middle section C, as is plainly shown in Figs. 1 and 2. From the lower end of the outermost section D extend downward the brackets D', supporting a pin D'', on which are pivoted the catches J and J', held between the brackets D', and pressed outward by a U-shaped spring K, secured by its ends to the free ends of the said catches J and J', and extending with its bent end into the lower end of the section D. Each of the catches J or J' is provided with a shoulder J'', adapted to be engaged by the edge of the handle-section B, in order to move the outermost section D outward into the position shown in Fig. 2, and as hereinafter more fully described.

In order to hold the outermost section D in place when extended, as shown in Fig. 2, a lug L is adapted to engage the lower edge of the section D, said lug L being secured on a spring L', fastened to the outside of the middle section C directly under the brace-piece I. The lug L extends through an aperture in the section C to the inside of the latter, so as to engage the lower end of the section D, when the latter is moved in an outermost position, as shown in Figs. 2 and 8, so that an exterior collar D''' on the lower end of the said section D abuts against an interior annular flange C', formed on the upper end of the middle section C. The collar D''' and the flange C' serve to prevent the displacement of the section D on the section C.

On the lower end of the middle section C is formed on the inside an annular flange C'', adapted to be engaged at its upper edge by the lower edge of an exterior collar B', formed on the upper end of the handle-section B. (See Fig. 2.)

In order to lock the handle-section B in place on the middle section C when the umbrella is extended, the lugs N are provided, which pass through apertures C''' in the section C into the upper end of the handle-section B, as illustrated in Fig. 2. The lugs N are secured to spring-levers N', fulcrumed at N'' to the outside of the middle section C. When the operator presses on the spring-pressed levers N', the lugs N are withdrawn

from the inside of the middle section C, so as to permit of sliding the handle-section B upward into the middle section C.

The under side of the lug L, previously described, is provided with a bevel L², adapted to be engaged by the upper end of the handle-section B, so as to move the said spring-pressed lug L outward to permit the closing of the outermost section.

10. Each joint-plate G is provided with a lug G', adapted to be engaged at opposite sides by shoulders F³ and F⁴, respectively, formed on the pivot ends of the parts F' and F², respectively, of each rib F. This device prevents the rib-parts F' and F² from bending outward after the rib is extended.

The operation is as follows: When the umbrella is in a folded position, as shown in Fig. 1, the rib parts F' and F² of each rib F extend parallel with each other, as shown, the covering passing over the outside of the rib part F' and over the inside of the rib part F², as indicated in dotted lines on the left of the said figure. When the operator now 25 desires to extend the umbrella, he takes hold of the rib parts F² with one hand and then pulls on the handle-section B, so as to withdraw the latter, until the upper end of the said handle-section B snaps under the spring-pressed catches J and J' to engage the under side of their shoulders J². The operator then takes hold of the handle-section B and shoves the latter inward, so as to exert a pressure against the catches J and J', which, by being pivoted to the outermost section D, shove the latter outward until the exterior collar D³ rests against the annular inner flange C' and the spring-pressed lug L has snapped under the inner end of the outermost section D. When 35 the outermost section D slides outward, the parts F' exert a pull on the joint-plates G, so that the latter swing outward and carry along the respective braces H, and at the same time the rib parts F² are moved downward into line 40 with the upper rib parts F'. The braces H then extend in about a horizontal position and hold the ribs F firmly in an extended position. The operator then takes hold of the middle section C and again pulls on the handle B, so that the latter slides outward in the middle section C until the collar B' on its upper end engages the inner flange C² on the lower end of the middle section C and the spring-pressed lugs N snap over the upper 45 ends of the said handle-section B, so as to lock the latter in place on the middle section C. The umbrella is then extended, and is used in the usual manner. When the operator desires to close the umbrella, he first presses on 50 the spring-levers N', so as to withdraw the lug N to unlock the handle-section B, which is now shoved into the middle section C. The upper end of the latter first engages the shoulders J² of the spring-catches J and J', so as to 55 close the same, which must take place, as the section D is stationary and offers the necessary resistance, the spring K at the same time

permitting such closing of the catches. The latter thus pass into the handle-section, which, with its upper end, now presses against the 70 beveled under side L² of the lug L to move the latter outward, the inner side of the lug resting on the outside of the handle-section B. By thus moving the lug L from under the lower end of the outer section D the latter is 75 unlocked, and is shoved into the handle-section by the operator exerting a slight pressure onto the outer end of the said section D. The ribs F on the inward movement of the section D swing inward, and are then folded by swinging the outer parts F² upward into the position shown in Fig. 1.

The umbrella when folded takes up very little room and can be conveniently placed in a pocket, valise, or other receptacle when not 80 in use.

Having thus fully described my invention, I claim as new and desire to secure by Letters Patent—

1. A cane for umbrellas, consisting of three 90 telescopic sections, the lower one of which engages the upper one to push it out of the middle section, substantially as described.

2. A cane for umbrellas, consisting of three telescopic sections, the upper section sliding 95 in the middle section and in the upper end of the lower section and adapted to be engaged by the lower section to project it, substantially as herein shown and described.

3. In an umbrella, the combination, with a 100 cane, of sectional ribs and joint-plates, to which each of the rib-sections and the braces are pivoted, substantially as and for the purpose set forth.

4. In an umbrella, the combination, with a 105 cane formed of three telescoping sections, of ribs, each consisting of two sections, joint-plates, to which the ends of each of the rib-sections are pivoted, and braces pivoted to the joint-plates, the upper end of the upper 110 section of the ribs being pivotally connected with the upper section of the cane and the braces with the middle section thereof, substantially as herein shown and described.

5. In an umbrella, the combination, with a 115 cane formed of three telescoping sections, of ribs, each consisting of two sections, joint-plates, to which the adjacent ends of the sections of the ribs are pivoted, having a lug between the ends of the said ribs, braces pivoted to the said joint-plates below the pivots of the rib-sections, the upper ends of the upper rib-sections being pivoted to the upper cane-section and the braces to the middle cane-section, substantially as herein shown 120 125 and described.

6. In an umbrella, a cane comprising a middle section, a handle-section held to slide in the said middle section, an upper section held to slide in the said middle section and adapted to pass into the said handle-section, and spring-pressed catches held in the inner 130 end of the upper section and adapted to be engaged by the upper end of the said handle-

section to extend the upper section, substantially as shown and described.

7. In an umbrella, the combination, with an upper cane-section, of a middle section in which the said upper section is held to slide, and a spring-pressed lug held on the said middle section and adapted to engage the lower end of the said upper section to lock the sections together when extended, substantially as described.

8. In an umbrella, the combination, with an upper cane-section, of a middle section in which the said upper section is held to slide, a spring-pressed lug held on the said middle section and adapted to engage the lower end of the said upper section to lock the sections together when extended, and a handle-section

held to slide in the said middle section and adapted to engage the said spring-pressed lug to hold the same out of contact with the upper section when the sections are telescoped, substantially as shown and described.

9. In an umbrella, the combination, with a handle cane-section, of an upper cane-section fitted to slide in the said handle cane-section and spring-pressed catches held on the said upper section and provided with shoulders adapted to be engaged by the said handle cane-section, substantially as shown and described.
